Jack Diamond, New York, N. Y., assignor to Hel-
bros Watch Company, Inc., New York, N. Y.

Application December 9, 1949, Serial No. 6,522

Term of patent 3½ years

(Cl. D42—8)

To all whom it may concern:

Be it known that I, Jack Diamond, a citizen of the United States, residing at New York, in the county of New York and State of New York, have invented a new, original, and ornamental Design for a Watch, of which the following is a specification, reference being had to the accompanying drawing, forming part thereof.

In the drawing:

Fig. 1 is a top plan view of a watch, showing my new design;

Fig. 2 is a side elevational view;

Fig. 3 is an end elevational view; and

Fig. 4 is a bottom plan view of the same.

I claim:

The ornamental design for a watch, as shown.

JACK DIAMOND.
